Attest:

UNITED STATES PATENT OFFICE

JOHN M. GRIBBLE, OF CHICAGO, ILLINOIS, ASSIGNOR TO SHAKEPROOF LOCK WASHER COMPANY, OF CHICAGO, ILLINOIS, A CORPORATION OF DELAWARE

ELECTRICAL CONNECTER

Application filed February 2, 1929. Serial No. 337,048.

My invention relates to electrical connectors and particularly to the type of connectors adapted to be clamped in position upon terminal posts and the like by screw heads or other similar clamping members.

One of the primary objects of my present invention is to provide a connector adapted for association with the terminal of an electrical conductor which is so designed as to permit of its being inserted beneath a binding screw head or the like without the necessity of first completely removing the screw, said connector being also configurated so as to present work engaging teeth which serve to secure said connector against inadvertent displacement.

Another object of my invention is to provide a connector as above set forth for association beneath the head of a binding screw, said connector being provided with a marginal abutment which will serve effectively to prevent said connector from being disassociated from the screw until the same has been backed off a predetermined amount.

Still more specifically, my invention contemplates the provision of an electrical connector which, in addition to the marginal abutment as above described, is also provided with a plurality of work engaging teeth which are twisted out of the plane of the connector body, thereby providing effective means for preventing the inadvertent backing off or loosening of the screw.

These and numerous other objects will be more apparent from the following detailed description when considered in connection with the accompanying drawings, wherein—

Figure 1 is a plan view of an electrical connector embodying features of my invention, said connector being secured to the terminal of a flexible conductor or wire, an associated binding screw being shown by dot and dash lines;

Figure 2 is a perspective view of a detached connector of the type shown in Figure 1;

Figure 3 is a central sectional view taken substantially along the line 3—3 of Figure 1;

Figure 4 is an end view of said connector as viewed from the right of Figure 3, the

binding screw and terminal post being shown in full lines as distinguished from the dot and dash lines of Figures 1 and 3;

Figure 5 is a plan view of a modified or flat type connector, the same being provided with a flat type shank adapted to be connected with the terminal of a conductor; and

Figure 6 is a sectional view taken substantially along the line 6—6 of Figure 5, a binding screw and post being shown by dot and dash lines.

Referring now to the drawings wherein like numerals have been employed to designate similar parts throughout the various figures, it will be observed that in Figures 1 to 4 inclusive I have disclosed an electrical connector indicated generally by the numeral 10 which is representative of one embodiment of my present invention. This connector 10 comprises a body portion 12 which is provided at one end with a shank 14. This shank 14 is adapted to encircle the terminal of a conventional flexible conductor or wire 16 as clearly shown in Figures 1 and 3. The other end of the body 12 is provided with an aperture 18 which is designed to readily permit the connector 10 to be inserted between the head of a conventional binding screw 20 and another work surface such as the upper extremity of a terminal post 24. The inner portion of the opening or slot 18 is shaped to conform with the threaded portion of the screw 20 and a marginal portion of a body 12 adjacent said slot is provided with a plurality of prongs or teeth 26, the corners of which are twisted out of the plane of the body 12. These teeth provide very effective means for securing the binding screw 20 against inadvertent displacement.

In the particular embodiment of the invention shown in Figures 1 to 4 inclusive I have shown the body portion 12 as being provided with a marginal abutment or flange 28. This flange 28 provides an effective means for positively preventing the disassociation of the connector from the binding screw until said screw has been backed off a predetermined amount. Thus, in order to remove the connector from the binding screw it is necessary to move the screw head through a distance 100

which is sufficient to permit the upper edge of the flange 28 to clear the lower surface of said screw head. The provision of this marginal abutment not only prevents the disengagement of the connector when the screw is initially loosened but also prevents the connector from being forced laterally of the screw when the head thereof is being tightened against the connector. There is a normal tendency for a slotted connector to be forced laterally of the screw when the head is being tightened thereagainst and this tendency is positively counteracted by the abutment or flange 28 which, under such circumstances, is moved into engagement with the periphery of the screw head, thereby preventing further lateral displacement of the connector. In other words, the abutment prevents the connector from slipping off while the screw is being tightened and also prevents the connector from slipping off until the screw has been backed off sufficiently to permit the flange and the twisted teeth to pass under the head.

25 In Figures 5 and 6 I have disclosed a flat type connector or terminal indicated by the numeral 10—a which includes a flat body portion 12—a and a flat shank 14—a formed integral therewith. The outer end of the shank 14—a is provided with apertures 30 which are adapted to receive the terminal of a flexible conductor. The body 12—a is formed with a slot 18—a which corresponds to the slot 18 in Figures 1 to 4 inclusive and bordering a portion of this slot 18—a is a plurality of twisted or warped locking teeth 26—a. The corner portions of these teeth 26—a like the corner portions of the teeth 26 are projected out of the plane of the body portion in a position to effectively interlock with the work between which they are clamped. The connector 10—a differs from the connector 10 in that the marginal abutment or flange 28 is not employed.

45 From the foregoing it will be apparent that my invention contemplates the provision of electrical connectors or terminals of improved design which are very simple to manufacture and which may be very conveniently used in connection with radio parts and other electrical apparatus. By providing the slot in the body portion of the connector said connector may be very conveniently positioned or removed without necessitating the complete backing off of the screw and this arrangement is decidedly advantageous in instances where the screws are positioned in rather inaccessible places. Thus for example in radio and other similar electrical equipment, binding screws are often positioned within cabinets or casings which render the same more or less inaccessible. In most instances these screws can be reached by inserting a screw driver but in the event

60 that they are completely unscrewed it is

often difficult to replace the screws by reason of the limited space surrounding the same. The twisted teeth serve not only to lock the binding screw in position but also insure proper electrical contact between the connector and the adjacent parts. The marginal abutment 28 provides an additional means for securing the connector against inadvertent displacement. The connector cannot slip off until the binding screw has been reversed sufficiently to enable the abutment and the teeth to pass beneath the screw head and this arrangement provides an additional safe guard against the tendency of terminals to become inadvertently disconnected. As hereinbefore set forth, this marginal abutment or flange also provides a stop which counteracts the tendency for the connector to be shifted laterally of the screw when said screw is being tightened thereagainst.

Having thus described my invention, what I claim as new and desire to secure by Letters Patent is:

An electrical connector formed from an integral piece of resilient flat stock including a shank portion for receiving the terminal of a conductor, an enlarged section having an elongated aperture, said aperture presenting a mouth at the side of the enlarged section for laterally receiving a terminal screw, a plurality of teeth warped out of the plane of the resilient stock of said enlarged section so as to present corners on opposite sides thereof, said teeth being formed integral with said enlarged section adjacent the inner portion of said elongated aperture and adapted to insure electrical contact and prevent inadvertent loosening of the screw, and a marginal flange extending laterally of and formed integral with the enlarged section, said flange terminating at the mouth of said elongated aperture and providing means whereby said connector cannot be removed from a screw until the head thereof has been moved out of contact with respect to said twisted teeth.

In witness whereof, I have hereunto subscribed my name.

JOHN M. GRIBBIE.
